US0D1083508S

(12) **United States Design Patent** (10) **Patent No.:** **US D1,083,508 S**
(45) **Date of Patent:** **** Jul. 15, 2025**

(54) **HYDRATION RESERVOIR**

(71) Applicant: **HydraPak LLC**, Oakland, CA (US)
(72) Inventor: **Kevin Somarriba**, Hayward, CA (US)
(73) Assignee: **HydraPak LLC**, Oakland, CA (US)

(**) Term: **15 Years**

(21) Appl. No.: **29/840,916**

(22) Filed: **Jun. 1, 2022**

(51) **LOC (15) Cl.** **07-01**

(52) **U.S. Cl.**

USPC **D7/509**

(58) **Field of Classification Search**

(57) **CLAIM**

The ornamental design for a hydration reservoir, as shown and described.

DESCRIPTION

FIG. 1 is a top front isometric view of a hydration reservoir showing the new design;

FIG. 2 is a bottom rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dashed lines shown in the drawings illustrate portions of the hydration reservoir that form no part of the claimed design.

1 Claim, 6 Drawing Sheets
